CLAIM

The ornamental design for a flower box air conditioner as shown and described.

DESCRIPTION

FIG. 1 is a front perspective view of the flower box air conditioner;

FIG. 2 is a front elevation view of the flower box air conditioner of FIG. 1;

FIG. 3 is a rear elevation view of the flower box air conditioner of FIG. 1;

FIG. 4 is a right side elevation view of the flower box air conditioner of FIG. 1;

FIG. 5 is left side elevation view of the flower box air conditioner of FIG. 1;

FIG. 6 is a top view of the flower box air conditioner of FIG. 1;

FIG. 7 is a bottom view of the fitness platform of FIG. 1; FIG. 8 is a perspective view of the flower box air conditioner in an environmental structure; and,

FIG. 9 is another perspective view of the flower box air conditioner of FIG. 8.

The broken lines in FIGS. 8 & 9 depict an environmental structure of the flower box air conditioner and form no part of the claimed design. The broken lines in the interior of the flower box air conditioner in FIGS. 1 & 9 depict portions of the flower box air conditioner that form no part of the claimed design.
